UNITED STATES PATENT OFFICE.

EDWARD J. BRADY, OF CEDAR FALLS, IOWA, ASSIGNOR TO IOWA GATE COMPANY, OF CEDAR FALLS, IOWA, A CORPORATION OF IOWA.

GATE-LATCH OR THE LIKE.

1,280,653.

Specification of Letters Patent.

Patented Oct. 8, 1918.

Application filed August 2, 1916. Serial No. 112,753.

To all whom it may concern:

Be it known that I, EDWARD J. BRADY, a citizen of the United States, residing at Cedar Falls, in the county of Blackhawk 5 and State of Iowa, have invented certain new and useful Improvements in Gate-Latches or the like, of which the following is a description.

My invention belongs to that general class 10 of devices known as gate latches, and relates particularly to a device for locking swinging gates, the same being particularly adapted for that style of gate that may be swung in either direction. The invention 15 has among its objects the production of a gate latching device of the kind described that is simple, convenient, durable, efficient and satisfactory, that will not easily get out of order nor be affected in its operation 20 by weather conditions, and which may be used wherever found applicable. The invention has particularly among its objects the production of a device that will securely and automatically lock or secure the gate 25 against opening, regardless of whether the gate is of the rigid or tilting type, or of wood, steel or other material. It has among other objects the production of a device that will not be rendered inoperative or ineffi- 30 cient when the gate sags or is tilted, or if the fence or gate posts should sag or settle, and which cannot be accidentally operated by stock or otherwise. It has among other objects the production of a device which 35 may consist of a plurality of locking elements or arms, all of which may be operated or controlled simultaneously in a simple manner, but which elements are independently operative and controllable, so that in 40 case any of the elements are not operated or are rendered inoperative, for any reason whatsoever, the efficiency and effectiveness of the device will not be impaired, but that the operative parts will perform their usual 45 functions and accomplish the result desired. Many other objects and advantages of the construction herein shown and described will appear to those skilled in the art from the disclosure herein made.

50 To this end my invention consists in the novel construction, arrangement and combination of parts herein shown and described, and more particularly pointed out in the claims.

In the drawings, wherein like reference 55 characters indicate like or corresponding parts,

Figure 1 is a view in elevation of an adjustable tilting type of gate with my latch applied thereto; 60

Fig. 2 is a front elevation of one of the latching devices, a portion slightly broken away to more clearly show the construction;

Fig. 3 is a similar view of the same with 65 the gate engaging member thrown to one side;

Fig. 4 is a front elevation of a portion of the complete device, the upper portion being partially shown in section; 70

Fig. 5 is a top elevation of the same;

Fig. 6 is a sectional view taken substantially on lines 6—6 of Fig. 4;

Fig. 7 is a perspective view of one of the fork engaging members; 75

Fig. 8 is a sectional view taken substantially on line 8—8 of Fig. 4;

Fig. 9 is a side elevation of a portion of the device;

Fig. 10 is a sectional view, similar to Fig. 8, illustrating a slight modification;

Fig. 11 is a sectional view taken substantially on line 11—11 of Fig. 10, and

Fig. 12 is a front elevation of the device, illustrating the independent action and control of the parts. 85

Referring to the drawings, in which the preferred embodiment of the invention is shown, 1 and 2 represent any style of fence or gate posts between which is arranged the gate which, as previously stated, may be the rigid type or that type known as a tilting gate, that illustrated being adapted to swing in either direction. Referring particularly to Fig. 1, the gate shown consists of the end 90 bars 3 and 4, and connecting bars 5 and 6, the parts being suitably connected in any desired manner. The gate may be covered with any suitable wire, wire netting or fabric, this depending on the particular use 95 to which the gate is to be put. In the gate shown end bar 3 is pivotally secured to and supported by the post 1, the opposite end being the free end of the gate, which may be swung in either direction past the post 2. The gate illustrated is of the tilting or adjustable type, so that the free end of the gate 100 may be raised or lowered as desired, the 105

locking device being applicable for the same, regardless of its adjustment or the means for supporting the free end of the gate.

The complete latch or lock illustrated in the drawing consists substantially of two or more latch or locking devices arranged to be actuated or controlled as one, or in some cases independently, it being understood that only one latch in some cases might be desirable. A description of one of the devices will suffice for both or for any number, as they are substantially identical, with the exception of the slight differences hereinafter referred to. It is immaterial whether or not the devices are placed on the gate post and arranged to engage the end bar of the gate or on the gate and arranged to engage the gate post, but the first arrangement being preferred, I have illustrated that.

Each latch preferably consists of a base plate 11, provided with a pair of extending parallel flanges 12 and 13, arranged one above the other. These are formed with the shoulders or abutments 14 and 15 (see Figs. 3 and 9) and the plate is preferably recessed or cut away as shown at 16 (see Fig. 8). I also provide an inclined or cam face 17 on each side intermediate the shoulders 14 and the face of the plate, the purpose being more fully described hereafter.

Carried between the flanges is a gate engaging member 18, or latch, provided with the extending arms 19, the same forming substantially a V-shaped member or fork arranged to embrace the bar 4 when the gate is closed (see Fig. 5), the ends of the fork 19 being preferably enlarged so as to guard against injury to stock that might rub against the same in passing through the gate opening. In the preferred construction shown, I pivotally secure the member 18 between the flanges by a tubular pin or bushing 20, 21 being a spring washer which may be inserted as shown to act as a brake or yieldingly oppose the pivoting movement of part 18 about the pin 20. The pin 20 is shown with the tubular opening tapered as at 22, and the same is supported in place by the shoulder or flange 23 formed on flange 13. Tapering the pin 20, as shown, prevents binding on the rod.

As was before mentioned, two latching devices are shown as constituting the complete latch or lock. Extending through the tubular pins 20 on the upper and lower flanges, as well as through any intermediate pins, in case more than two latch devices are employed, is an operating or latch release controlling rod 24, which carries means for engaging the several members 18. I have shown two forms of engaging or latch locking members, the same being substantially similar, except that the upper one is capped over, as will be hereinafter referred to. The upper member 25 is shown in Figs. 4, 5, 6

and 7, and consists of the part 25 formed with a chamber or recess 29 therein, hooded or closed at the top, the same having a depending leg or fork engaging member 27 at each side. In the construction shown the recess in the head is elongated rather than circular. The member 26 is substantially identical, the legs 28 being similar to the legs 27 of the upper member, except that the top is open so that the rod 24 may pass therethrough. Obviously, member 26 might be employed at the top of the rod in lieu of member 25, and in the case of intermediate latches, members similar to 26 would ordinarily be employed. The members 25 and 26 are secured to the rod by means of the pins 30, or their equivalents, for the purpose. As is obvious, the head locking members may be tilted on the operating rod without binding. I preferably place a collar or stop 31 at the lower end of the rod, and, if desired, a spring 32 may also be arranged as shown (see Fig. 6).

In the modified construction shown in Figs. 10 and 11, 2 represents the fence post, 36 the plate carrying the flanges, between which is arranged the forked member 37. 39 represents the legs of a fork engaging member. In this case, in lieu of the spring washer previously described, or supplemental thereto, I roughen the top face of the fork member, as at 38, and similarly form the lower end of the legs 39, as shown at 40 in Fig. 11. This tends to retard the movement of the forked member and prevent back throw when the gate is thrown from one side to the other.

The operation of the devices may be briefly explained as follows: Assuming that the gate is shut, so that the forks and fork engaging members and rod 24 are substantially as shown in Figs. 1, 4, 5, 6 and 8, if it is desired to open the gate, the same is released by raising the rod 24, thereby raising the fork engaging members. (See Fig. 2, in which engaging member 26 is raised). Pressure applied on the gate will cause movement of the fork members substantially as indicated in Fig. 3, and by the dotted lines in Fig. 5, the legs 27 and 28 being raised out of engaging position between the shoulders 14 and 15 on the base plate and shoulders 18' on the forked member, as shown in Fig. 8. The fork member moves sufficiently to release the gate end bar 4, permitting the gate to be swung open as much as desired. The fork members remain in their adjusted or open position so as to engage the gate when again moved to closed position. Any back throw or accidental movement is normally prevented by the spring washers 21, these acting substantially as yielding brakes. Of course as soon as the forked members have moved sufficiently so that the fork members are under the ad-

ja⁵cent leg 27 or 28 of the fork engaging members, the rod 24 may be released so that the fork engaging members substantially take the positions shown in Fig. 3. It will be noted by referring to this figure that while one leg is carried or supported by the fork member, the other leg is in a position to engage the shoulder 18' at the opposite side of the forked member when the gate 10 is swung to closed position. As soon as it is swung to this closed position and shoulder 18' engages the leg of the engaging member, the engaging member drops into position to engage the shoulder on the other 15 side, thereby not only stopping the movement of the gate, but automatically engaging the fork so as to lock the gate shut until the parts are again manipulated as described. It is obvious that the operation 20 would be the same regardless of how many forks were employed.

The device is operative if only one fork is engaged, so that the efficiency or operation of the device is in no way impaired in 25 case the gate is tilted sufficiently to engage only one fork, or if the gate or gate posts should sag or otherwise get out of normal arrangement the device would still be operative. This may best be described by referring to Fig. 12, in which the upper fork is shown in closed or locking position by the full lines and by dotted lines as thrown to the right, while the lower fork is shown as thrown to the right. Assuming that both 30 forks are to the right and the gate is opened, the upper fork and engaging member will be as indicated in the dotted lines, and the lower fork and engaging member as indicated in the full lines. In this case it will 35 be noted that the pins 30 are in engagement with the lower end of the slots 29 in the members 25 and 26. Assume that the gate is moved to closed position, but that the lower fork is not engaged or moved, the 40 upper fork being moved to the position shown in the full lines: As soon as the fork reaches the closed position shown the leg 27 will drop down so as to engage behind the shoulder, locking the fork against 45 movement. The member may drop to engaging position, due to the slot 29, even though the rod 24 does not drop. Referring to Fig. 12, it will be noted that in the dotted lines the locking member rests one side upon 50 one of the flanges, this point being substantially a fulcrum point, so that when the latch is moved to closed position the leg 27 (Fig. 12) moves faster than the ordinary drop, due to gravitation on account of the 55 leverage at the fulcrum point mentioned. In case that the upper fork is not moved, but the lower fork moved back, member 26 would likewise drop into operative engaging position by virtue of its weight and 60 leverage, so that the lower pin 30 would

engage in the upper end of the slot 29 of part 26. This is important, as while the devices, regardless of the number of forks, may be simultaneously released or locked, they are also independently operable.

Owing to the open spaces between the shoulders 14, 15 and 18', the parts are freely operable and but slightly affected by weather conditions. In case the rod carrying the fork engaging member should turn 75 or partially rotate, owing to the cam or beveled faces 17, the fork engaging members will be guided to operative position, thereby bringing the rod back to proper adjustment. From the above description it 80 will be seen that the device is substantially applicable for any type or style of gate.

Having thus described my invention, it is obvious that various immaterial modifications may be made in the same without departing from the spirit of my invention, hence I do not wish to be understood as limiting myself to the exact construction, arrangement or combination of parts herein 85 shown and described, or uses mentioned.

What I claim as new and desire to secure by Letters Patent is:—

1. A gate latch of the kind described, comprising a base plate having a flange projecting from the face thereof, a gate latching member carried thereby, and means for pivotally securing said member on said plate, means for engaging said member and normally preventing the pivotal movement thereof, comprising a locking member having extending legs of a length to project between the plate and said latch member, and vertically movable means for supporting said locking member.

2. A gate latch of the kind described, comprising a base plate having a flange projecting from the face thereof, a gate latching member carried thereby, and means for pivotally securing said member on said plate, means for engaging said member and normally preventing the pivotal movement thereof, comprising a locking member having extending legs of a length to project between the plate and said latch member, and vertically movable means for tiltably supporting said locking member.

3. A gate latch of the kind described, comprising a base plate having a flange projecting from the face thereof, and formed with shoulders at each side of said flange, a latching member carried by said flange, and having shoulders thereon adjacent the shoulders at said flange, but spaced therefrom, a tubular pin extending through and pivotally securing said member on said flange, a rod extending through said tubular pin and slideable therein, and means carried by said rod for engaging said shoulders and normally preventing the pivotal movement of the latch member.

125

130

4. A gate latch of the kind described, comprising a base plate having a flange projecting from the face thereof and formed with shoulders at each side of said flange, a latch-
5 ing member carried by said flange, and having shoulders thereon adjacent the shoulders at said flange, but spaced therefrom, a tubu-
10 lar pin extending through and pivotally se-
curing said latch member on said flange, a
15 rod extending through said tubular pin and
slidable therein, an inverted U-shaped lock-
ing member provided with a depending leg
at each side of a size to extend between and
coöperate with said shoulders and formed
20 with an opening through the same interme-
diate the said legs, said locking member
mounted on said rod, and means for adjust-
ably securing said member to the rod.

5. In a gate locking device of the kind
25 described and in combination, a base plate
provided with two horizontally extending
flanges and formed with shoulders at the
sides thereof, a U-shaped member arranged
25 between the said flanges with the legs of
the U extending therefrom, said member
having shoulders formed thereon at the
base of the U, a tubular pin carried by said
flanges and extending through said U-shaped
30 member, a rod extending through said pin,
and a locking member carried by said rod,
said member provided with extending parts
arranged to normally project between the
shoulders at the flanges and the shoulders on
35 said U-shaped member, said rod slidably
through said pin a distance sufficient to
raise the locking member, whereby the ex-
tended parts thereof will clear the shoulders
on said U-shaped member, and permit the
40 pivotal movement thereof about said pin.

6. In a gate latching device of the kind
45 described and in combination, a base plate
provided with a pair of spaced flanges, and
formed with shoulders at each side of said
flanges, the plate at the upper flange in-
clined upwardly from the shoulders to the
50 face of the plate, a U-shaped gate engaging
member having shoulders on each side at the
base of the U, a tubular pin carried by said
flanges and projecting from the base of the
55 U-shaped member, a rod extending through
said pin and slidably therein, a locking mem-
ber adjustably carried by said rod, and pro-
vided with depending legs, one at each side
of the rod, said legs each of a size to pro-
ject between the shoulders on the base plate
and the adjacent shoulder on the U-shaped
member, and coöperate therewith.

7. In a gate latching device of the kind
60 described and in combination, a base plate
provided with a pair of spaced flanges, and
formed with shoulders at each side of said
flanges, the plate at the upper flange inclined
upwardly from the shoulders to the face of
65 the plate, a U-shaped gate engaging member
having shoulders on each side at the base

of the U, a tubular pin carried by said
flanges and projecting through the base of
the U-shaped member, a rod extending
70 through said pin and slidably therein, a
locking member adjustably carried by said
rod and provided with depending legs, one
at each side of the rod, said legs each of a
size to project between the shoulders on the
75 base plate and the adjacent shoulder on the
U-shaped member, said locking member tilt-
ably carried by said rod and adjustable
lengthwise thereof.

8. In a gate locking device of the kind de-
scribed and in combination, a base plate hav-
ing spaced flanges with shoulders on each
80 side, a U-shaped latch member carried be-
tween the flanges, and having a shoulder on
each side, a tubular pin tapered internally
and extending through said latch member,
said lower flange formed with a seat for the
85 lower end of said pin, a U-shaped locking
member arranged above said flanges, with
the legs of the U projecting downwardly in
the path of the latch member between the
shoulders on the base plate and latch mem-
90 ber, said locking member formed with an
elongated opening therein, and with an
elongated hole through the same on opposite
sides, a rod extending through said tubular
pin and into the opening in said locking
95 member, and a pin extended through said
rod and the elongated holes in said locking
member.

9. In a gate locking device of the kind de-
scribed and in combination, a base plate hav-
ing projecting flanges on one face thereof, a
forked latch member pivotally carried there-
100 by, a latch locking member arranged above
said latch member, consisting of an inte-
grally formed U-shaped member arranged
105 to engage the latch member and lock the
same against pivotal movement, and verti-
cally movable supporting means for lifting
said latch locking member out of operative
110 position.

10. In a gate locking device of the kind de-
scribed and in combination, a base plate hav-
ing projecting flanges on one face thereof, a
forked latch member pivotally carried there-
115 by, a latch locking member arranged above
said latch member, consisting of an inte-
grally formed U-shaped member arranged
to engage the latch member and lock the
same against pivotal movement, and
means for lifting said latch locking member
120 out of operative position, comprising a slid-
able rod and a pin extended through a hole
in the rod and the locking member, the hole
in one part being elongated to permit rela-
tive movement of the parts lengthwise the
125 rod.

11. In a gate locking device of the kind de-
scribed and in combination, a pair of
plates carried one above the other, each pro-
vided with projecting flanges from the base
130

thereof with shoulders on each side of the flanges, a U-shaped latch member carried by each plate between the flanges thereof, and each having a shoulder on each side, an internally tapered tubular pin for each pair of flanges, each extending through the forked latch member, a rod projecting from and through the lower pin to and through the upper pin, a locking member for each latch member, the lower locking member formed with an opening therethrough and arranged on said rod, means for pivotally securing said locking member to the rod, and a locking member arranged at the upper end 15 of said rod, provided with a recess closed at its upper end over the top of the rod, means for securing the upper locking member to the rod, each of said locking members provided with depending legs adapted to normally extend between the shoulders on said plates and said latch members, and prevent the pivotal movement of the latch members about said tubular pins.

12. In a gate latching device of the kind described and in combination, a pair of plates arranged one above the other, each having a flange projecting from the face thereof, a latch member arranged on each flange member, a tubular pin carried by each flange and extending through and pivotally securing each latch member to its respective flange, a rod extending through said tubular pins, and slidale relative thereto, and means carried by said rod for normally engaging and preventing pivotal movement of said latch members about their respective pins.

13. In a gate latching device of the kind described and in combination, a pair of plates arranged one above the other, each having a flange projecting from the face thereof, a latch member arranged on each

flange member, a tubular pin carried by each flange and extending through and pivotally securing each latch member to its respective flange, a rod extending through said tubular pins, and slidale relative thereto, and means carried by said rod for normally engaging and preventing pivotal movement of said latch members about their respective pins, comprising a locking member adjustably carried by said rod adjacent the lower latch member, and a locking member adjustably carried adjacent the upper latch member.

14. In a gate latching device of the kind described and in combination, a pair of plates arranged one above the other, each having a flange projecting from the face thereof, a latch member arranged on each flange member, a tubular pin carried by each flange and extending through and pivotally securing each latch member to its respective flange, a rod extending through said tubular pins, and slidale relative thereto, and means carried by said rod for normally engaging and preventing pivotal movement of said latch members about their respective pins, comprising a locking member arranged at the upper end of the rod above the upper latch member, and means for tiltably and adjustably securing the same to the rod, and a latch member arranged adjacent the lower end of the rod above the lower latch member, and means for tiltably and adjustably securing the same to the rod.

In testimony whereof, I have hereunto signed my name in the presence of two subscribing witnesses.

EDWARD J. BRAJY.
